UNITED STATES PATENT OFFICE.

ST. JOHN WOOD, OF NEW YORK, N. Y.

PROCESS OF DIVIDING DIAMONDS.

No. 839,357.

Specification of Letters Patent.

Patented Dec. 25, 1906.

Original application filed May 3, 1906, Serial No. 315,109. Divided and this application filed August 13, 1906. Serial No. 330,434.

To all whom it may concern:

Be it known that I, ST. JOHN WOOD, of New York, in the county of New York and in the State of New York, have invented a certain new and useful Improvement in the Processes of Dividing Diamonds; and I do hereby declare that the following is a full, clear, and exact description thereof, reference being had to the accompanying drawings, in which—

10 Figure 1 is a perspective view of a rough diamond or crystal divided into slices or "wases." Fig. 2 is a plan view of a slice or was. Fig. 3 is a view of the first block removed from the slice or was. Fig. 4 is a 15 view of the second division of the slice or was. Fig. 5 is a view of the final division of the slice or was.

In the preparation of the diamond for sale to jewelers or consumers it is not always feasible to finish up each rough diamond into the largest gem it is possible to make therefrom, but because the demand for the largest gems is comparatively small it is necessary to divide a large proportion of rough diamonds to 25 form a number of small diamonds from each rough diamond. In my application for patent filed May 3, 1906, for "process of dividing diamonds," Serial No. 315,109, I have described a process of dividing a rough diamond or crystal so that the largest possible weight of smaller diamonds can be made from it. Prior to my said process the division of the larger crystals into several parts to make smaller diamonds has been accomplished by cleaving or splitting the rough diamond or crystal, and as such action can 35 usually take place only in planes parallel to the faces of the crystal it has prevented the division of crystals in planes so disposed as to give shapes from which the largest possible finished diamonds could be made, and a very 40 objectionable amount of waste has resulted from the use of this method. By the method which is the subject of my said prior application instead of using the wasteful method of cleaving or splitting I saw the body of the crystal through in any direction, and I discovered that this could be done without in 45 the least fracturing the diamond or otherwise injuring its purity or affecting its value. As I was thus able to divide the crystal in any direction, I devised a method of dividing the crystal by which a maximum weight of 50 smaller finished diamonds could be produced

from a large crystal, and I found in practice 55 that by using my process I effected a most important saving in material and very greatly increased the value of the finished product from a given-sized crystal as compared with the product of cleaving or splitting. 60

The process of dividing diamonds, which is the subject of the present application for patent, is a special application of the process of the aforesaid application to the division of a slice or was of a peculiar shape. 65

In practicing my present invention I first divide the crystal into slices or wases, as illustrated in Fig. 1. The average slice or was has three sides to its larger face, and ordinarily these sides are of equal length. 70 With some crystals, however, a slice or was is obtained of the shape illustrated in Fig. 2, in which there are two long sides *a* and *b*, connected by a short side *c*. In order to divide the said slices into blocks from which 75 the finished diamonds are to be obtained, I first saw into a slice from the side *a* or the side *b* near the point *d*, where the sides *a* and *b* meet, the saw cut *e* penetrating to about the longitudinal center of the slice. I then 80 make a saw cut *f* from the opposite side to meet saw cut *e*, and thus remove a block *g* from the point of the was. I then form a saw cut *h* through the longitudinal center of the slice or was and divide it into two parts 85 *i* and *k*, as illustrated in Figs. 3 and 4, which are each again divided by saw cuts that are preferably substantially perpendicular either to the outer or inner edges thereof.

By this method I divide the slices into 90 blocks which produces a much larger weight of finished diamonds than is possible by the old method of cleaving, since by cleaving all of the divisions would have to be in planes parallel to a face of the was. 95

I claim—

1. The process of dividing an elongated slice or "was" of a large diamond to form smaller diamonds, which consists in removing a block from the point of the slice by divisions starting on opposite sides of such point and meeting at an angle to each other, separating the remainder of the slice by a central longitudinal division, and dividing the two portions thus formed by transverse 100 divisions. 105

2. The process of dividing an elongated slice or "was" of a larger diamond to form

smaller diamonds, which consists in removing a block from the point of the slice by two cuts starting on opposite sides of such point and meeting at an angle to each other, dividing the remainder of the slice by a central longitudinal saw cut, and dividing the two portions thus formed by transverse saw cuts.

In testimony that I claim the foregoing I have hereunto set my hand.

ST. JOHN WOOD.
